EYESHADE

Nicholas A. Linster, Mansfield, Ohio

Application May 11, 1953, Serial No. 353,965

4 Claims. (Cl. 2—10)

This invention relates to an eyeshade that is especially designed for use by golf players.

It is well known that the great majority of amateur golfers have trouble keeping their heads down with their eyes on the ball when making a shot. They are so anxious to see where the ball is going that they quickly look up towards the end of their swing. Generally this is just before the club head hits the ball which results in a poor shot for it is essential for a good shot that one see the club head strike the ball. Many golfers say or think to themselves when addressing the ball preparatory to making a shot, "Keep your head down." A better slogan would be "See the club head hit the ball."

I have found by experience that if a player's vision is restricted, when making a shot, to the small area around the ball this tendency to "look up" too soon is greatly minimized. With this in mind I have provided an eyeshade visor, which is adapted to extend forwardly from one's head above their eyes, with a pair of flaps which extend downwardly from each side of the visor in position to restrict the wearer's vision straight forwardly. In order that a player's vision will not be restricted when walking between shots I mount the flaps upon the visor in such a manner that they can be quickly and easily moved back and forth between their vision restricting position and a position above and substantially parallel to the visor.

The principal object of the invention is to provide an eyeshade with constraining means by which a wearer's vision is restricted straight forwardly.

Another object of the invention is to provide an eyeshade with vision constraining means which is so constructed that it can be quickly and easily moved back and forth between operative and inoperative position.

Another object of the invention is to provide a vision constraining means of the aforesaid character which can be easily applied to the visors of caps or eyeshades.

Other and more limited objects of the invention will be apparent from the following specification and the accompanying drawings forming a part thereof wherein:

Fig. 1 is a view showing a golf player wearing an eyeshade constructed according to my invention, in the act of making a shot;

Fig. 2 is a plan view of an eyeshade constructed accordingly to my invention;

Fig. 3 is a side elevation thereof showing the eyeshade in position upon a player's head with the visor constraining flaps in operative position;

Fig. 4 is an enlarged fragmentary perspective view showing one of the flaps in operative position; and

Fig. 5 is a transverse section taken on the line 5—5 of Fig. 4.

Referring now to the drawings by reference characters the numeral 1 indicates a visor which is secured to a cap 2 by which the visor 1 is removably held upon a player's head in position to extend forwardly therefrom above the eyes. A pair of aligned tubular tracks 3 having slots 4 extending from end to end along one side thereof are se-

2

cured by tongues 5 to the upper surface of the visor 1, one at each side thereof with the outer ends 6 of the tracks extending out slightly beyond the side edges 7 of the visor. 1. The slots 4 at the outer ends 6 of the tracks 3 terminate in rearwardly and downwardly extending extensions as shown at 8 in Figs. 4 and 5.

A ball 9 is slidably and rotatably mounted in each of the tracks 3. The balls 9 carry clips 10 which extend out through the slots 4 and have flaps 11 secured by rivets 12 to the outer ends thereof. The flaps 11 may be made of any suitable light stiff opaque material and the clips 10 are preferably secured thereto intermediate the ends thereof.

When used to constrain one's vision during the making 15 of a shot the flaps 11 extend substantially vertically downwardly from the sides 7 of the visor 1 with the rear ends 14 thereof in contact with a user's face slightly rearwardly of his eyes as shown in Fig. 4. From the point of contact with a player's face the flaps 11 extend forwardly 20 substantially parallel with the side edges 7 of the visor 1 with the forward ends 15 of the flaps 11 disposed a substantial distance in front of the eyes.

When it is not desired to use the flaps 11 to restrain 25 one's vision as when a player is walking between shots the flaps are adapted to be disposed over the visor 1 in a position substantially parallel thereto as shown in Fig. 2.

In moving the flaps 11 from the inoperative position shown in Fig. 2 to the operative position shown in Figs. 3, 4 and 5, they are first pulled straight outwardly from 30 the full line positions shown in Fig. 2 to the dotted line positions A shown in Fig. 2 in which position the balls 9 are at the ends 6 of the tracks 3. The flaps 11 are then turned from the dotted line positions A in Fig. 2 to the dotted line positions B in Fig. 2, after which they are 35 swung downwardly into engagement with the sides of one's face as shown in Fig. 3. In returning the flaps 11 back from operative position to inoperative position they are first swung up to the dotted line position B, and then turned to the dotted line position A, after which they are 40 pushed inwardly into position over the visor 1, all as shown in Fig. 2.

The device may be easily and quickly applied to the visor of any cap or eyeshade of usual construction by cutting properly positioned slits therein and then inserting 45 the tongues 5 therethrough and bending them over as shown in Fig. 5.

From the foregoing it will be apparent that I have provided a very simple, efficient, and inexpensive device for restricting one's vision as desired for the purpose described.

50 Although I have shown and described my improved eyeshade in connection with its use by golf players it will be understood that it can be used equally well in connection with other pursuits where it is desired to restrict one's vision straight forwardly. For instance it could be used 55 by bowlers to restrict their vision to the alley on which they are bowling.

It is to be understood that I am not limited to the specific construction shown and described herein as various modifications may be made therein within the scope of the appended claims. For instance the tracks 3 could be applied to the underside of the visor 1 in which case the flaps 11 when not in use would be disposed under the visor instead of over the visor as shown. Also tracks could be mounted along the side edges 7 of the visor and the flaps arranged to slide back and forth along the tracks and to be swung out of position either over or under the visor.

What is claimed is:

1. An eyeshade for golf players comprising a visor, means by which said visor is adapted to be removably secured to a player's head in position to extend forwardly therefrom above the eyes, a flap carried by said visor, said

flap being adapted in one position to project substantially perpendicular to said visor and to extend forwardly along one side edge thereof and in another position to be disposed over said visor substantially parallel thereto, means securing said flap to said visor for movement back and forth between said positions, said securing means comprising a transverse tubular track having a longitudinal slot therein secured to the upper surface of said visor, a ball slidably and rotatably mounted in said tubular track, a clip carried by said ball and extending out through said slot with the outer end of said clip secured to said flap.

2. An eyeshade for golf players comprising a visor, means by which said visor is adapted to be removably secured to a player's head in position to extend forwardly therefrom above the eyes, a pair of flaps carried by said visor, said flaps being adapted in one position to project substantially perpendicular to said visor and to extend forwardly along each side edge of said visor and in another position to be disposed over said visor substantially parallel thereto, means securing said flaps to said visor for movement back and forth between said positions, said securing means comprising a pair of transverse tubular tracks secured to the upper surface of said visor, a longitudinal slot in each of said tracks, a ball slidably and rotatably mounted in each of said tracks, a clip carried by each of said balls and extending out through their associated slots with the outer end of each of said clips secured to one of said flaps.

3. An eyeshade for golf players comprising a visor, means by which said visor is adapted to be removably secured to a player's head in position to extend forwardly therefrom above the eyes, a flap carried by said visor, said flap being adapted in one position to project substantially perpendicular to said visor and to extend forwardly along one side edge thereof and in another position to be disposed over said visor substantially parallel thereto, means

securing said flap to said visor for movement back and forth between said positions, said securing means comprising a transversely extending track permanently secured to the upper surface of said visor with one end thereof disposed adjacent one side edge of said visor, a slide carried by said track for rotary and longitudinal movement with respect thereto, and interengaging means between said slide and said flap by which said flap is permanently secured to said slide for movement therewith.

4. An eyeshade for golf players comprising a visor, means by which said visor is adapted to be removably secured to a player's head in position to extend forwardly therefrom above the eyes, a pair of flaps carried by said visor, said flaps being adapted in one position to project substantially perpendicular to said visor and to extend forwardly along each side edge of said visor and in another position to be disposed over said visor substantially parallel thereto, means securing said flaps to said visor for movement back and forth between said positions, said securing means comprising a pair of transversely extending tracks permanently secured to the upper surface of said visor with one end of each of said tracks being disposed adjacent a side edge of said visor, a pair of slides, one of said slides being carried by each of said tracks for rotary and longitudinal movement with respect thereto, and means by which each of said flaps is permanently secured to one of said slides for movement therewith.
